GOGGLES

Paul Amundsen, Evanston, Ill., assignor to Fendall Company, Chicago, Ill., a corporation of Illinois

Filed Oct. 18, 1957, Ser. No. 690,967

1 Claim. (Cl. 2—14)

This invention relates to eye protective devices in the form of goggles or spectacles, adapted to be worn in manufacturing plants, shops, and other places by mechanics and workmen for the protection of the wearer's eyes against flying particles.

Various forms of eye protective devices, in the form of goggles, spectacles, and the like, have been known and used heretofore. However, one of the defects common to all of such prior eye protective devices, including goggles, spectacles, and the like, has been the fact that all of the same have left an unprotected area about and between the nose of the wearer and the frame and shield of the goggles or spectacles, through which small flying particles could travel and enter the eyes of the wearer.

Accordingly, an object of the present invention is to provide a new and improved eye protective device in the form of goggles, or spectacles, and which is so constructed and arranged that foreign particles are effectively prevented from entering the wearer's eyes through the area about and around the nose of the wearer and between the nose and the frame of the goggles or spectacles.

Another object of the present invention is to provide a new and improved eye protective device in the form of goggles or spectacles embodying a flexible shield attached to the goggles or to the spectacles in such a manner that in use it conforms to the shape of the bridge of the nose of the wearer and effectively closes the area about and between the nose and the frame or shield of the eye protective device and prevents foreign particles from entering into the eyes through this area.

A further object of the present invention is to provide a new eye protective device in the form of goggles embodying a flexible shield member which is adapted to be detachably attached to the nose bridge portion of the goggles frame and which in use is adapted to conform to the shape of the bridge of the nose of the wearer and effectively prevent foreign particles from entering the eyes through this area.

An additional object of the invention is to provide a new eye protective device embodying a flexible shield member for the purpose described above, and which is permanently attached to the nose bridge portion of the goggles frame.

A further object of the invention is to provide an eye protective device of the spectacle type and which embodies a flexible shield which is attached to the spectacles so as to close the area around and about the nose, and between the nose and the nasal sides of the spectacles, so as to prevent foreign objects or particles from entering into the eyes of the wearer through this area.

Other objects will appear hereinafter.

In the drawings:

Fig. 1 is a front elevational view of an eye protective

2

device in the form of goggles embodying a typical form of the present invention;

Fig. 2 is a sectional plan view of line 2—2 in Fig. 1;

Fig. 3 is a sectional plan view of line 3—3 in Fig. 5;

5 Fig. 4 is a central vertical sectional plan view on line 4—4 in Fig. 1;

Fig. 5 is a fragmentary vertical sectional view showing the flexible auxiliary shield member in position of use on

10 the wearer of the eye protective device, or goggles which is shown in Figs. 1 to 4, inclusive;

Fig. 6 is a fragmentary front elevational view of the new eye protective device embodying the construction shown in Figs. 1 to 5, inclusive, and illustrating the means for detachably attaching the flexible auxiliary shield member to the nose portion of the frame of the goggles;

Fig. 7 is a front elevational view showing the nose bridge portion of the frame of the goggles to which the flexible auxiliary shield member is attached in the form of the invention shown in Figs. 1 to 6, inclusive;

20 Fig. 8 is a plan view showing the flexible auxiliary shield member embodied in the form of the invention shown in Figs. 1 to 7, inclusive;

Fig. 9 is a fragmentary front elevational view of a modification of the invention in which the flexible auxiliary shield member is formed as an integral part of the

25 goggles frame, rather than as a separate unit, as in the form of the invention shown in Figs. 1 to 8, inclusive;

Fig. 10 is a sectional plan view on line 10—10 in Fig. 9;

30 Fig. 11 is a central vertical sectional view on line 11—11 in Fig. 9;

Fig. 12 is a front elevational view showing another modification of the invention as applied to an eye protective device in the form of spectacles;

35 Fig. 13 is a sectional plan view on line 13—13 in Fig. 12;

Fig. 14 is a central vertical section view on line 14—14 in Fig. 12; and

Fig. 15 is a plan view of the flexible auxiliary shield 40 member embodied in the form of the invention showing Figs. 12 to 14 inclusive.

A typical embodiment of the present invention is illustrated in Figs. 1 to 8, inclusive, of the drawings, and is there shown as being embodied in an eye protective device in the form of goggles, generally indicated at 10, and including a frame 11 which is preferably molded of suitable flexible transparent synthetic resinous plastic material, and which includes a main or primary transparent, resinous plastic shield member 12. The frame 11 includes bosses 13 at the sides thereof and to which are attached suitable fastening means, such as an elastic strap 14, for detachably mounting the new eye protective device on the head of the wearer.

45 As is customary in the art, the plastic resinous frame 11 may be provided with suitable vent openings, such as 22, as shown in Fig. 2.

The frame 11 includes a nose bridge portion 15, which is provided with a rearwardly and upwardly extending flexible tongue portion 16, which is adapted to be formed of flexible plastic resinous material, and an arcuate generally triangular-shaped slot 21 is provided in the nose bridge portion 15 of the frame 11, as shown in Figs. 6 and 7.

50 In the practice of the present invention I provide an auxiliary flexible and preferably transparent resinous shield member 17, which is generally triangular in shape, and which includes a main body portion 18 which in-

cludes a pair of spaced wing portions "W." The auxiliary shield member 17 is preferably made in the form of a sheet of any suitable transparent resinous plastic material such, for example, as polyvinyl chloride, but may be made of natural latex rubber, or a synthetic copolymer elastomer or the like, and includes an upper latching tongue portion 19, which includes a pair of spaced laterally extending latching ears 20, which are connected to the main body portion 18 of the flexible auxiliary shield member 17 by a web portion 23.

In the practice of the form of the invention shown in Figs. 1 to 8, inclusive, the flexible auxiliary shield member 17 is detachably mounted on the frame 11 by projecting the flexible latching tongue portion 19 thereof through the slot 21 so that the latching ears 20 extend out beyond the outer marginal edges of the slot 21 and thus retain the auxiliary shield member 17 in position of use on the frame 11, inwardly or rearwardly of the primary shield member 12. The insertion of the latching tongue 19 through the slot 21 is made possible by the fact that the flexible auxiliary shield member 17 and the latching tongue portion 19 thereof are made of flexible resinous plastic material which may be bent or folded slightly laterally to enable the latching tongue portion 19 to be inserted through the slot 21.

It will be noted that when the auxiliary shield member 17 is in position of use on the frame 11, as shown in Figs. 1 to 6, inclusive, the wing portions "W" thereof extend laterally some distance beyond and on opposite sides of the nose bridge portion 15 of the frame 11 and over portions of the primary shield member 12, inwardly of the latter.

However, when the user mounts the new eye protective device or goggles 10 in position of use upon his head the flexible auxiliary shield member 17 will conform, under the pressure of the nose of the wearer thereagainst, to the shape of the bridge of the nose of the wearer, and take the form shown in Figs. 3 and 5. When so disposed the body portion 18 and the wing portions "W" of the auxiliary shield member 17 embrace the bridge of the nose of the wearer and this action forces the body portion 18 of the auxiliary shield member 17 into engagement with the top and side edges of the nose bridge portion 15 of the frame 11. Thus the auxiliary shield member 17 closes the area between the nose bridge portion 15 of the frame 11 and the nose and face of the wearer and thereby prevents foreign particles from passing through this area into the eyes of the wearer, thus overcoming a difficulty experienced in the use of prior eye protective devices.

A modification of the invention is illustrated in Figs. 9 to 11, inclusive, and in this form of the invention those parts thereof which are similar to corresponding parts embodied in the form of the invention shown in Figs. 1 to 8, inclusive, of the drawings have been given the same reference numerals followed by the additional and distinguishing reference letter "a."

The form of the invention shown in Figs. 9 to 11, inclusive, differs from that shown in Figs. 1 to 8, inclusive, the flexible preferably transparent auxiliary resinous plastic shield member 17 is molded, in the form of a relatively thin flexible sheet, as an integral part of the nose bridge portion 15 of the frame 11 and, from which it depends by a relatively narrow web portion 24, which corresponds in purpose, to the latching tongue portion 19 in the form of the invention shown in Figs. 1 to 8, inclusive.

In use, the form of the invention shown in Figs. 9 to 11, inclusive, operates in substantially the same manner, and equally as effectively as the form of the invention shown in Figs. 1 to 8, inclusive, and as hereinbefore described.

Another modification of the invention is illustrated in Figs. 12 to 15, inclusive of the drawings, and in this

form of invention the new eye protective device is shown as being embodied in a spectacle type of eye protective device which is generally indicated as 25, and which includes a frame 26. The frame 26 includes a shield-supporting frame elements 24 and 27 and a nose bridge member 28 which cooperates with the parts 24 and 27 for retaining the primary shield member 29 in the assembly. Suitable bows 30 are pivotally connected to the sides of the frame 26, as at 31.

In the form of the invention shown in Figs. 12 to 15, inclusive, the auxiliary flexible shield member is indicated at 32 and includes a body portion 33 which is generally triangular in shape and is preferably made of suitable transparent flexible synthetic plastic resinous sheet material, and includes a pair of wing portions "WB" which correspond to the wing portion "W" in the form of the invention shown in Figs. 1 to 8, inclusive.

In the form of the invention shown in Figs. 12 to 15, inclusive, the flexible transparent auxiliary shield member 32 is attached to the primary shield member 29 by means of suitable fastening elements in the form of small screws 34 and a small attaching plate 35. The fastening elements or screws 34 are inserted through holes 36 formed in the relatively narrow upper portion of the body 33 of the auxiliary shield member 32 and through corresponding holes in the main or primary shield member 29, and a retaining plate 35 is mounted on the fastening elements or screws 34, inwardly of the auxiliary shield member 37.

In the use of the form of invention shown in Figs. 12 to 15, inclusive, when the eye protective spectacles 25 are mounted in position of use on the wearer's face, the flexible auxiliary shield member 32 will conform to the shape of the bridge of the nose of the wearer, in the same manner as in the use of the form of the invention shown in Figs. 1 to 8, inclusive, and as shown in Figs. 3 and 5, and when so used the auxiliary shield member 32 effectively closes the area between the nose of the wearer and the main or primary shield member 29, and thus prevents foreign particles from passing through this area into the eyes of the wearer.

It will thus be seen from the foregoing description, considered in conjunction with the accompanying drawings, that the present invention provides a new and improved eye protective device which may take the form of goggles, spectacles, or the like, having the desirable advantages and characteristics, and accomplishing the intended objects, including those hereinbefore pointed out, and others which are inherent in the invention.

I claim:

In a device for protecting the eyes having a frame portion which includes a lens section and a nose bridge section, the combination therewith comprising a substantially flat resilient nose piece having a substantially straight upper edge, curved ends and a curved lower edge, the upper edge including a locking tab extending in the same plane as the nose piece and having a neck portion and an enlarged head portion, the nose bridge section having a slot at the apex thereof extending into the interior of the device, the tab inserted in the slot and held therein by its enlarged head portion, the slot having a length substantially equal to the width of the neck portion, the nose bridge of the device including downwardly and outwardly curved portions, the nose piece overlapping said downwardly and outwardly curved portions inward of said lens section and as the device is positioned over the wearer's head slidably engaging along the curved lower edge the downwardly and outwardly curved portions of the nose bridge, the nose piece, during positioning, being pushed through the nose bridge opening outward of said frame portion of the device such that when seated in wearing position the nose piece will automatically conform to the curvature of the nose of the wearer and at the same time conform to the down-

wardly and outwardly curved portions of the device thereby preventing the entrance of small particles within the device along the nose bridge thereof.
